UNITED STATES PATENT OFFICE

2,274,315

FUEL INJECTION SYSTEM OR DEVICE FOR
INTERNAL-COMBUSTION ENGINES

George Amery, Oldbury, England

Application November 24, 1939, Serial No. 305,971
In Great Britain November 24, 1938

6 Claims. (Cl. 299—107.6)

This invention comprises improvements in or relating to fuel injection systems or devices for internal-combustion engines.

It is an object of the invention to provide an alternative form of fuel-injector to that described in United States Patents No. 2,150,574 and No. 2,053,311.

In the aforesaid United States patent there is described an injection system in which a fuel-injector is provided with a needle-valve to control the flow of fuel through the nozzle and the needle-valve is opened by fuel pressure acting upon an opening-piston, which fuel pressure is continuously maintained and is closed by the application of fluid pressure, at the desired time of closing, to a closing-piston capable of overcoming the action of the opening-piston. In this construction the opening-piston and the passage to the fuel-jet opening are subject to the same fluid pressure. The inverse arrangement has also been proposed, namely to maintain the pressure on the closing-piston continuously and to vary the pressure periodically on the opening-piston, which was to have an effective area larger than the closing-piston.

According to the present invention, in a fuel injection system in which a fuel-injector is provided having a fuel-jet opening and valve therefor controlled by an opening-piston and a closing-piston and wherein pressure on the opening-piston is varied periodically to determine the opening and closing of the valve, there is provided an opening-spring to assist the opening action of the opening-piston.

The opening-piston may be of an effective area equal to, or smaller than, that of the closing-piston. Closing pressure may be applied by the continuous supply of fuel to the closing-piston and the closing-piston may be in communication with a passage leading to the valve seating of the fuel-jet opening. The opening-piston is not then in direct communication with the passage leading to the valve seating and the fuel-jet opening. As in the case of the said prior patent the valve is shut by the fuel pressure while pressure is still fully maintained at the valve seating.

The invention further comprises in a fuel injection system in which an injector is provided having a fuel-jet opening and a valve therefor provided with an opening-piston and a connection from a distributor thereto so that the valve is opened by the periodic application of pressure under the control of the distributor to the opening-piston, the provision of an auxiliary cut-off valve in a fuel passage leading to the fuel-jet,

which cut-off valve is subject to the action of said pressure from the distributor so that the shuttle valve opens the said passage when the distributor applies pressure to the opening-piston and closes it when the distributor pressure is released or diminished from said piston. Thus pressure is cut off from the valve seating and jet opening immediately after the valve is closed and is not reapplied until the application of pressure to the opening-piston moves the cut-off valve over when the valve at the jet opening is to be opened again, and any undesired leakage of the fuel into the engine cylinder at periods when the injection is supposed to be cut off is thus prevented.

The following is a description, by way of example, of constructions in accordance with the invention, reference being made to the accompanying drawing in which—

20 Figure 1 is a longitudinal section through an injector not having an auxiliary cut-off valve, and

25 Figure 2 is a similar view of another injector working on the same principle as Figure 1 but provided with an auxiliary cut-off valve.

Referring to Figure 1 the fuel injector comprises a body portion 11 having a central axial bore 12. To the body 11 there is secured by a union nut 13 a nozzle 14 having in the tip fuel-jet openings 15 and a seating 16 behind the inner ends of said openings 15 on which seating a needle-valve 17 is adapted to close. The needle-valve 17 fits closely within the nozzle 14 and is provided with grooves 18 to diminish leakage. Around the end of the needle-valve between the cylindrical portion which fits the bore in the nozzle and the seating 16 there is an enlargement 19 of the internal bore of the nozzle 14 which constitutes a pressure chamber, and from this when the needle-valve is opened fuel can flow through the jet openings 15 into the engine cylinder.

Within the body 11 is a reaction-nut 20 seated against which is a spring 21 and the spring 21 bears on a shouldered pressure member 22 which in turn bears through a ball 23 on the stem 24 of the needle-valve 17. Thus the spring tends to keep the needle-valve closed.

Secured on the body 11 by means of a union nut 25 is a control section 26 which contains a control chamber 27. The control chamber 27 has a cylindrical bore, coaxial with the other parts of the injection nozzle, in which works a control piston 28. The piston 28 has a piston rod 29 (sealing the chamber 27) which passes

down through the reaction nut 20 and bears by the rod 30 on the back of the shouldered pressure member 22. The parts 28, 29 and 30 may be separate parts, if desired, to avoid difficulties due to the problem of securing exact concentricity of all the various bores. Between the control extension 26 and the reaction member 20 there is inserted a spring washer 31 to prevent the reaction member from unscrewing under vibration, while permitting it to remain in any desired position of adjustment, so that the effective pressure of the spring 21 can be varied.

Coaxial with the end of the control extension 26 is a nipple 32 for connection to a supply pipe for fuel under injection pressure. It will be observed that this pressure acts on the piston 28 in a direction to close the needle-valve 17 through the intermediary of the piston rods 29 and 30 and the pressure member 22. By means of passages 33, 34 and 35 drilled respectively in the control section 26, the injector body 11 and the nozzle 14 the fuel oil is conveyed to the pressure chamber 19 behind the needle-valve seating 16.

Within the control chamber 27 there is a strong spring 36 which acts upon the piston 28 in a direction to oppose and partly balance the closing pressure of the injection fuel. In the side of the control extension 26 there is a passage 37 which is connected by a connector 38 to a distributor pipe. It will be observed that the connector 38 surrounds the cylindrical exterior of the control extension 26 closely and has a screwed boss 39 on one side seated in which is a double-cone nipple 40, so that a suitable screwed end on the distributor pipe can be easily coupled up to it in a pressure-tight manner. The passage 37 leads into the control chamber 27.

The face of the piston 28 which abuts upon the spring 36 constitutes an opening piston which is, however, of smaller effective area than the other face, which constitutes a closing-piston. However, by the aid of the spring 36, should pressure be applied by the distributor through the passage 37 to the opening-piston this will be sufficient to cause the needle-valve 17 to open, the injection pressure acting on the needle-valve 17 being sufficient to overcome the resistance offered by the spring 21. The needle-valve 17 itself has a certain area, as will be seen from the drawing, which acts as an assistance to the opening-piston in opening the needle-valve but the combined effective areas taken together do not reach the area of the closing face of the piston 28, and the spring 36 therefore fulfils an essential function in ensuring the opening of the needle-valve against the continuous pressure of the fuel in the closing direction.

No closing spring is provided acting on the piston 28 as the fuel under pressure acting continuously on the piston 28 in the closing direction tends at all times to press the piston towards the needle-valve 17.

An outlet for seepage is provided at 41 and this may be provided with a nipple and a connection to a drain pipe if desired.

The distributor and the fuel supply connections may be operated as described in my prior United States Patent No. 2,150,574 with the exception that the valves and operating mechanism of the distributor are modified so that pressure is applied through the passage 37 from the distributor whenever the injection is to take place instead of applying pressure during the periods when injection is to be prevented. It will

therefore be appreciated that (provided the proper fuel pressure is available) whenever injection is to take place the needle-valve 17 is caused to open by the application of pressure through the passage 37 and when injection is to terminate this pressure is released or diminished, thus permitting the needle-valve 17 to be closed under the influence of the fuel pressure applied through the nipple 32 and of the spring 21. In all other respects the control may be as described in my aforesaid United States patent and in United States specification Serial No. 225,025 and the present invention therefore provides an alternative form of injector to that described in the said prior specification.

In the injector as illustrated in Figure 1 of the drawing the fuel pressure is maintained continuously in the pressure chamber 19 and the seating 16 is therefore the sole means of preventing leakage of the fuel into the engine cylinder at other times than that at which injection is to take place, but in my aforesaid United States Patent No. 2,150,574 I have described an auxiliary cut-off valve which is operated by the distributor pressure so as to prevent the pressure at the needle-valve seating from being applied at the times at which it is not required.

An auxiliary cut-off valve for this purpose may also be provided according to the present invention and the construction shown in Figure 2 shows this.

Referring to Figure 2, this comprises a nozzle body 50 having secured to it by a union nut 13 a nozzle 14 similar to that of Figure 1 and containing a needle-valve 17. The needle-valve 17 is closed by a spring 21 operating through a pressure member 22 and sustained by a reaction nut 20 as already described. Moreover, the nozzle body 50 is provided with a fuel passage 34 communicating with a passage 35 in the nozzle also as already described.

In the construction illustrated in Figure 2 the injector body 50 is enlarged eccentrically at the head end as indicated in the figure at 51 and the control section of the injector instead of being held on the end of it like the section 26 of Figure 1 is constituted by a cylindrical control section 52 which is enclosed within the enlargement 51 and held there by a screwed plug 53 on which a nipple 54 is formed for connection to the source of fuel under pressure.

The control section 52 contains a control chamber 27 as already described and a piston 28 which is acted upon by an opening spring 36. There is, moreover, a lateral connection 39 for a nipple of a distributor supply pipe and the general construction and operation of the parts is similar to that already described. In the side of the control section 52 which, owing to its eccentric disposition, forms a lateral extension of the control member to one side of the axis of the piston 28, there is a cross bore 55 containing a shuttle valve 56. The auxiliary cut-off valve 56 is open to the pressure in the control chamber 27 and is moved against this pressure by means of a return spring 51. Instead of the spring 57 there might be provided a connection from passage 59 so that the valve is returned by fuel-pressure. The auxiliary cut-off valve has a circumferential groove 58 about the middle of its length which is arranged, when the pressure in the chamber 27 forces the valve back against the spring 57, to be brought into register with a fuel passage 59 which is drilled in the control section 52 and serves to connect the high pressure supply

through the plug 53 with the fuel passages 34 and 35 before referred to. Thus when the distributor applies pressure through the connection 9 to cause the needle-valve to open the auxiliary cut-off valve is forced back and permits fuel pressure from nipple 54 to reach the seating of the needle-valve 17. At other times the spring 57 presses the valve 56 toward the control chamber 27 and shuts off the pressure from the lower part of the passage 59. At the same time a flat 60 in the underside of the valve 56 serves to connect the passage 59 below the valve 56 with a drain passage 61 in the control section 52, which drain passage leads to the central space around the piston rod 29. It will be appreciated that the piston rod 29 passes through the reaction nut 20 with a clearance so that the seepage past the needle-valve 17 can also find its way past the piston rod 29 into the same space as that to which the seepage passage 61 delivers any fuel from the shuttle valve 56. It is necessary to provide for this seepage being carried away from the nozzle and this is done in the following manner:

A packing washer 62 is provided between the control extension 52 and the bottom of the recess in the body 50 within which the extension 52 is located. Against this packing washer the extension 52 is forced by means of the screwed plug 53 before referred to. The packing washer is, however, slightly smaller in diameter than the flat face on which it rests, so that an annular fuel passage is provided around it. A radial channel 63 in the body 50 below the packing washer 62 connects the central space around the piston rod 29 with the annular passage and a channel 64 in the periphery of the extension 52 connects the annular passage around the packing washer 62 with the bore of the shuttle valve beyond the passage 59. A further channel 65 in one side of the bore of the shuttle valve ensures communication with the space in which the spring 57 is located and from here there is a seepage passage 66 which may, if desired, be connected by a suitable nipple to a drainage pipe. If the valve 56 is returned by fuel pressure instead of by spring 57 the drain must be located elsewhere for example as outlet 41 in Figure 1.

In order to prevent the valve 56 from rotating in the construction illustrated, so that the flat 60 ceases to register with the passages 59 and 61, it has a stem 67 which is provided with a flat on one side and a grub screw, not shown in the drawing, bears on this flat and thus prevents its rotation.

In the operation of this device it will be seen that the application of pressure in the pressure chamber 27 will serve not only to open the needle-valve 17 but also to push open the shuttle valve 56, thus admitting pressure to the pressure chamber 19. As soon as this pressure is cut off the shuttle valve 56 is pushed over and connects the pressure chamber 19 to the leakage outlet so that fuel pressure is prevented from acting on the seating of the needle-valve 17 except at such times as it is required to remain open for injection purposes. The needle-valve 17 will in practice close against the full fuel pressure in the chamber 19 and the shuttle valve 56 will cut off this pressure immediately upon the closing, but not before, because the shuttle valve cannot move over to alter the connection until the pressure in the control chamber 27 has fallen below 75

that which is required to sustain the needle-valve 17 open.

When the valves are opened, owing to the lightness of the shuttle valve and to the fact that it has a large pressure face compared with its weight and the strength of its spring, it will open even more rapidly than the needle-valve 17 so that there will be no lag between the opening of the needle-valve and the commencement of spraying. This is further assisted by the fact that at the opening stage until the shuttle valve 56 is opened the effect of the opening pressure on the needle-valve 17 itself, which tends to assist the opening pressure on the piston 28, cannot occur.

The construction and operation of a fuel-nozzle in accordance with the present invention are particularly convenient owing to the fact that the control section containing the operating piston 28 can be removed from the back of the nozzle body 11 without interfering with the injection nozzle 14 or the necessity of taking apart the intermediate elements. Furthermore the quantity of fuel necessary to operate the parts through the distributor connection 39 is very small and thus a minute quantity of fluid entering from the distributor connection will cause the needle-valve to open and the release of this minute quantity will cause it to shut, thus ensuring prompt operation and avoiding wide fluctuations of fluid in the pressure pipe lines and parts connected thereto.

Although in the system as hereinabove described the opening- and closing-pistons are actuated by fuel under injection pressure it is to be understood that these pistons might be operated in accordance with the invention by another fluid than the fuel, operating if desired under another pressure, and in this case the size of the pistons and/or the strength of the spring will be modified so as to secure the necessary force for operating the parts.

In another alternative construction instead of connecting the passage 33 to the space behind the closing piston face of the piston 28 (Figure 1) may be connected to the control chamber 27. In this case if the passage opens into the wall just above the opening piston face of piston 28 when the valve 17 is closed, the piston 28 will cut off the fuel from the passage 34 and act as a kind of auxiliary cut-off valve.

I claim:

1. A fuel-injector comprising in combination an injector-body, a fuel-jet opening therein, a valve chamber, a valve for closing said fuel-jet opening, a spring for holding said valve on its seating, a piston face upon said valve for opening same against said spring under fuel pressure in said valve chamber, a cylindrical chamber providing a control cylinder in said body in line with said valve, a piston in said control cylinder, a compression member extending in sealed relation with said cylindrical chamber from said piston into engagement with said valve, means for admitting fuel under pressure to the piston face on said piston which is remote from said valve and to said valve-seating, a spring bearing on the other piston face of said piston to assist the movement of the piston away from said valve and means for admitting fluid under pressure to said other piston face.

2. A fuel-injector as claimed in claim 1, wherein the control cylinder is located in a separate control section of the injector-body detachably secured thereto.

3. A fuel-injector comprising in combination an injector-body, a fuel-jet opening therein, a valve chamber, an inwardly opening valve for said opening, a cylindrical chamber providing a control cylinder in said body in line with said valve, a control piston in said cylinder, means connecting the control piston with said valve, a fuel passage leading to the valve seating and fuel-jet opening, an auxiliary cut-off valve in said passage, which valve is provided with a piston face in communication with the portion of said control cylinder which is nearer the valve, so that pressure in said portion control cylinder serves to move the auxiliary cut-off valve to open said fuel passage at the same time that the control piston is operated to move away from the first said valve, and means to return said auxiliary cut-off valve when pressure in said portion of control cylinder is diminished to close said fuel passage.

4. A fuel-injector for a system as claimed in claim 3, wherein the auxiliary cut-off valve is located within a control section containing the

control piston, and wherein the control section is detachably secured to the body of the injector.

5. A fuel-injector as claimed in claim 3, wherein the auxiliary cut-off valve is removable from the injector-body through a removable nipple in the wall thereof.

6. In a fuel injection system the combination of a fuel-injector body, a fuel-jet opening therein, a valve for said fuel-jet opening, a cylindrical control-chamber, a piston in said control chamber, means operatively connecting said piston to said valve, an opening spring operatively connected to said piston to assist opening of the valve and means to supply fuel under pressure to said control chamber on the face of said piston such as to close said valve against the spring said fuel supply means having also a conduit open to the seating of said valve, and separate means to supply fuel under pressure to the other face of said piston to assist in opening the valve.

GEORGE AMERY.
